ALARM SIGNALING SYSTEM

Charles F. Ffolliott, Chicago, Ill., assignor to Associated Electric Laboratories, Inc., Chicago, Ill., a corporation of Delaware

Application December 4, 1936, Serial No. 114,145

11 Claims. (Cl. 179—5)

This invention is concerned with alarm signaling systems and more especially an alarm system in which a plurality of alarm stations are provided and arranged for signaling alarm headquarters, and the general object of the invention is to provide new and improved circuit arrangements for systems of the foregoing character.

A further object of the invention is to provide an alarm system over which may be transmitted 10 two classes of alarms, and in which telephone communication may also be established between an alarm station and alarm headquarters.

An additional object of the invention is to provide new and improved arrangements for supervising the alarm circuits against trouble conditions thereon.

These and other objects and features, not specifically pointed out, will be apparent by referring to the accompanying drawings which together 20 with the detailed description constitute the preferred embodiment of the invention.

The invention is illustrated in three sheets of drawings, comprising Figs. 1, 2, and 3. The drawings, when laid out with Fig. 2 above Fig. 25 3, and with Fig. 1 at the left of Fig. 2, illustrate the apparatus and circuits of the preferred form of the invention.

Fig. 1 shows a single radial alarm box RB—1 connected by an individual pair of wires RC to 30 terminals of the main distributing frame MDF. The alarm transmitting equipment shown diagrammatically at RB—1 is preferably housed within a box, so arranged that the opening of the 35 associated door will cause the engagement of door contacts 103 and 106. After opening the door of the box access may be had to a fire alarm lever arranged to actuate contacts 112. The combined loud speaking receiving and transmitting unit 109 may be a so called sound power unit such 40 as is disclosed in the application of Woodruff et al., S. N. 738,030, filed August 2, 1934. The telephone equipment proper comprises two of the so called sound power units, preferably mounted together in the form of the telephone hand set 45 110, such a hand set is disclosed in the pending application of Sengebush, S. N. 738,186, filed August 3, 1934. One unit of the hand telephone functions as a receiver and the other as a transmitter.

50 At the bottom of the figure is shown a series alarm circuit SC across which are bridged a plurality of series alarm boxes, as the box SB—1. In structure and equipment the series boxes may be identical with the radial box shown at RB—1, the

circuit, however, has been modified as will be more fully pointed out hereinafter.

Fig. 2 shows terminal equipment TE, located at alarm headquarters, upon which may be terminated either a radial circuit, as shown at RC 5 of Fig. 1, or a series circuit as shown at SC. The terminal equipment, among other things comprises the line jack LJ and the trouble jack TJ. The telephone cord circuit CC may be plugged into a desired line jack, such as LJ; and the test cord circuit TC may be plugged into a desired test jack, such as TJ.

The terminal equipment individual to each alarm line also includes an alarm relay 223, which is responsive only to an alarm of the second class, and, for the purpose of description, will be referred to as the fire alarm relay.

Fig. 3 shows, diagrammatically, alarm retransmitting equipment also located at alarm headquarters, comprising a plurality of finder switches, 20 one of which may search for and seize an operated fire alarm relay, such as relay 223 of Fig. 2, thereby associating the same with the sender switch which next functions to transmit a code, indicative of the fire alarm relay in question, over 25 an outgoing alarm circuit. Alarm transmitting equipment such as above described is disclosed in the pending application of Lomax et al., S. N. 112,190, filed Nov. 23, 1936, wherein the finder sequence switch is shown as Fig. 3, the finder 30 switch as Fig. 2, and the sender and the sender sequence switch is shown in Fig. 4.

It is believed that a most thorough understanding of the invention can be obtained by describing the operation resulting first, from the transmission of a class one alarm; and second from 35 the transmission of a class two alarm.

Transmission of class one alarm

The transmission of class one alarms can best 40 be explained in connection with a patrol box system, here it is essential that emergency or "wagon" calls may be initiated by the officer with the minimum of exertion. Assuming a case of this kind, it is only necessary for the officer to 45 open the door of the alarm box RB—1, whereupon a circuit is established from the positive side of battery B, through relay 200, choke 201, winding 202 of repeating coil R—1, springs 203 of test jack TJ, conductor 100, jumper 101, line 50 conductor 102, door contact 103, choke 104, break contact of telephone switch hook 105, door contact 106, line conductor 107, jumper 108, conductor 204, springs 205, of test jack TJ, winding 206 of repeating coil R—1, choke 207, through relay 55

208 to the negative side of battery B. Relays 200 and 208 will now energize and close obvious circuits through both windings of relay 209 to battery. The two windings of relay 209 will assist each other and cause the complete operation of the said relay, whereupon a circuit is closed from ground at break contact of armature 210, armature 211, break springs 212 of line jack LJ, through line lamp 213 to battery. The lighting of line lamp 213 is, in itself, information sufficient to warrant the dispatching of the patrol wagon to the physical location of alarm box RB-1 associated therewith. The operator in attendance, however, in an attempt to gain additional information will select an idle cord circuit, such as the cord circuit CC, and insert the answering plug P-1 into the line jack LJ. After which the operator will depress the talking key K-1 and challenge. This challenge will be made audible at alarm box RB-1 by the loud speaking sound power unit 109. The said unit will also act as a microphone to pick up any word spoken in the vicinity of alarm box RB-1.

In the event that no emergency exists the officer, upon opening the box, will remove the hand set telephone 110 from the switch hook, thus bridging the same across the line in place of the loud speaking sound power unit 109, thereby insuring better transmission than could be expected over the loud speaking unit.

Upon completion of the conversation the officer will restore the telephone hand set to the switch hook and close the door of alarm box RB-1, thereby causing the deenergization of relays 200 and 208. Relay 209 will next deenergize and close a disconnect circuit from ground at armature 214, sleeve of jack LJ, sleeve of plug P-1, through disconnect lamp 215 to battery. The lighting of the disconnect lamp 215 will indicate that the door of alarm box RB-1 has been closed and the operator will remove the plug P-1 from the jack LJ.

In a system such as we have been discussing it is desirable that provision be made whereby the operator at alarm headquarters may "recall" or signal the various alarm stations. In case it is desired to recall alarm box RB-1 the operator will select an idle cord circuit, such as the cord circuit TC, and will insert the calling plug P-3 into the test jack TJ, after which the ringing key K-3 will be operated to impress generator on line RC. The ringer 111 at alarm box RB-1 will respond thereto and sound an audible signal or code.

55   *Transmission of class two alarm*

The transmission of class two alarms can best be explained in connection with a fire alarm system. In furtherance of this use the outside of box RB-1 preferably bears the notice, "To report fire, open door, pull lever down, and then let go". The opening of the door results in the circuit changes previously described, and the operation of the fire alarm lever causes the momentary interruption of a circuit extending from ground at fire alarm contacts 112, and thence in parallel through condensers 113 and 114, windings 115 and 116 of repeating coil R-2, line conductors 102 and 107, jumpers 101 and 108, conductors 100 and 204, springs 203 and 205 of test jack TJ, windings 202 and 206 of repeating coil R-1, conductors 217 and 218, through normally energized relay 219 and the alternating current generator A to ground. Relay 219 will fall away momentarily and close a circuit from ground at

spring 220 of the test jack TJ, armature 221, armature 222 and its make contact through fire alarm relay 223 and resistance 225 to battery. Relay 223, upon energizing, will lock its self up to ground at spring 220 of test jack TJ by way 5 of armature 224, and at armature 219 will remove direct ground from the circuit of lamp 213 and substitute therefor ground through interrupter INT.

The flashing of line lamp 213 is, in itself, information sufficient to warrant the dispatching of fire apparatus to the physical location of alarm box RB-1 associated therewith. The operator in attendance, however, in an attempt to gain additional information, will, as before explained, 15 select an idle cord circuit and insert the answering plug thereof into the line jack LJ.

A further result of the energization of fire alarm relay 223 is the establishment of circuits by way of armatures 226 and 227, and conductors 300, 20 301, and 302, to the alarm transmitting equipment indicated diagrammatically in Fig. 3, with the result that a finder switch therein will search for and find fire alarm relay 223, thereby associating the same with the common sender switch 25 which next functions to transmit a code indicative of fire alarm relay 223 over an outgoing alarm circuit. At the end of the required number of rounds of the code the sender sequence switch will function to shunt out fire alarm relay 30 223, thereby causing its deenergization.

At the bottom of Fig. 1 is shown a series alarm circuit SC across which are bridged a plurality of series alarm boxes which, in structure and equipment, may be identical with the radial box 35 shown at RB-1. It is to be noted, however, that only the repeating coil of one box has been bridged across the line, and that the alternating current circuit therefrom has been seriesed to ground through the fire alarm contacts of all 40 boxes on the line. The series circuit SC may be jumpered to terminal equipment such as TE of Fig. 2, and the functioning of the series box is identical with that described in connection with alarm box RB-1, but it is to be understood that 45 the line lamp associated with circuit SC is distinctive of that circuit, and not of a particular box thereon.

Supervision of alarm circuits

Attention is called to the fact that the alternating current circuit through relay 219 is simplex to ground at the mid-point of repeating coils R-1 and R-2, it follows then that relay 219 and the two repeating coils may be so selected that, in the event of an open circuit in one line conductor, the inductive reactance of the half coil at each end of the circuit will so reduce the current flow through relay 219 as to allow armature 221 to fall away and complete a circuit from ground at spring 220 of test jack TJ, armature 221, armature 222 and its break contact through line lamp 213 to battery. It is apparent also that relay 219 will deenergize either as a result of the loss of the ground connection at 60 alarm box RB-1, or the simultaneous opening of both line conductors.

It is further to be pointed out that the mid-point of battery B is connected to ground and, therefore, relays 200 and 208 serve as ground detectors. A ground in line conductor 102 will cause the energization of relay 200, while a ground on line conductor 107 will cause the energization of relay 208. The energization of either of the aforesaid relays will close a circuit 75

through one winding of relay 209, with the result that the latter relay will energize only sufficiently to operate armature 211, thereby closing a circuit through line lamp 213.

- 5 To summarize the foregoing it may be said that the line lamp 213 will light as a result of ground on either line conductor; a simultaneously opened circuit in both line conductors; the loss of ground at alarm box RB-1; an open circuit 10 in one line conductor; the opening of the door at alarm box RB-1; or the short circuiting of line conductors 102 and 107. As before explained, the operator, in response to the lighting of line lamp 213, will insert answering plug P-1 into 15 line jack LJ and challenge. If no reply is received to the challenge the operator will withdraw plug P-1 from jack LJ and insert plug P-3 of test cord circuit TC into the test jack TJ associated with alarm circuit RC. By further 20 operation of keys thereon the usual routine line tests may be made as, for instance, the foreign potential test established by key K-5.

Attention may also be directed to the fact that the transmission of a fire alarm code over 25 the alarm circuit may be initiated either before or after the operator inserts an answering plug into the line jack. And further, that a false fire alarm can occur only in the event of two simultaneous line faults, i. e., a short circuit on 30 the line at the same time that the line is open beyond the short circuit.

While the invention has been shown as used in a combined police and fire alarm system, it will be understood that it could be utilized equal- 35 ly as well in connection with any other signaling system such as watchman's service or supervisory signaling.

The invention having been described, that which is believed to be new and for which the 40 protection of Letters Patent is desired will be pointed out in the appended claims.

What is claimed is:

1. In an alarm system, an alarm station, an alarm headquarters, a line circuit connecting said alarm station with said alarm headquarters, a normal flow of alternating current over said line circuit, a source of direct current potential normally applied to said line circuit, an alarm signal at said alarm headquarters, means at said alarm station for interrupting said normal flow of alternating current when an emergency alarm is transmitted, means at said alarm headquarters responsive to said interruption of said normal flow of alternating current for interruptedly operating said alarm signal, means at said alarm station for permitting a flow of direct current from said source of direct current potential when an ordinary alarm is transmitted, and means at said alarm headquarters responsive to said direct current flow for steadily operating said alarm signal.

2. In an alarm system, an alarm station, an alarm headquarters, a line circuit connecting said alarm station with said alarm headquarters, a normal flow of alternating current over said line circuit, a source of direct current potential normally applied to said line circuit, telephone facilities at said alarm station, telephone facilities at said alarm headquarters, an alarm signal at said 70 alarm headquarters, means at said alarm station for interrupting said normal flow of alternating current when an emergency alarm is transmitted, means at alarm headquarters responsive to said interruption of said normal flow of alternating current for interruptedly oper-

ating said alarm signal, means at said alarm station for permitting a flow of direct current from said source of direct current potential when an ordinary alarm is transmitted, means at said alarm headquarters responsive to said direct current flow for steadily operating said alarm signal, and means at said alarm headquarters for establishing telephone communication with said alarm station over said line circuit. 5

3. In an alarm system, an alarm station, an alarm headquarters, a line circuit extending from said alarm station to said alarm headquarters, means for normally feeding alternating current to said line, means controlled by said alternating current for supervising said line 15 against open circuit faults, and means responsive to the turning in of an alarm at said station for feeding direct current over said line circuit to bring in an alarm at said headquarters.

4. In an alarm system, an alarm station, an alarm headquarters, a line circuit extending from said alarm station to said alarm headquarters, means normally feeding alternating current to said circuit for supervising said line against open circuit faults, a battery bridged across said line 25 having its mid-point connected to ground, means responsive to current flow from either half of said battery for supervising said line against ground faults, and means responsive to the turning in of an alarm at said station for feeding 30 direct current over said line circuit to bring in an alarm at said headquarters.

5. In an alarm system, a station, a central office, a line extending from said station to said office, a simplex circuit including said line, a source of alternating current at said office normally connected to said circuit, an alarm signal at said office, means at said station for interrupting the flow of alternating current in said simplex circuit, and means at said office operated 40 responsive to said interruptions in current flow for operating said signal.

6. In an alarm system, an alarm station, an alarm headquarters, a two-conductor line connecting said station and said headquarters, a simplex circuit including said line conductors, a source of alternating current at said headquarters, an alarm signal at said headquarters, an alarm signal relay at said headquarters connected in series with said source of current and said simplex circuit, said relay normally energized by current flow from said source to prevent the operation of said alarm signal, means at said station connected in series with said simplex circuit for interrupting the flow of alternating current over said circuit, said alarm signal relay deenergized responsive to the interruption of said current flow to permit said alarm signal to operate. 55

7. In an alarm system, a central office, an alarm station, a line connecting said station and said office, normally deenergized alarm signal initiating relays at said office, one of said relays connected in a circuit feeding direct current to one conductor of said line, the other one of said relays connected in a circuit feeding direct current to the other conductor of said line, an alarm signal at said office, ordinary alarm transmitting means at said station for completing an energizing circuit for said relays in series, means controlled responsive to the energization of said relays for operating said alarm signal steadily to indicate an ordinary alarm, a simplex circuit including said line conductors extending from said office to said station, a normal flow of alternating cur- 70 75

rent in said simplex circuit, emergency alarm transmitting means at said station for interrupting the flow of alternating current in said simplex circuit when an emergency alarm is transmitted, 5 emergency alarm signal initiating means at said office operated responsive to the interrupting of the alternating current in said simplex circuit for indicating an emergency alarm.

8. In an alarm system as claimed in claim 7, 10 in which the ordinary and emergency alarm transmitting means at said station is so arranged that the ordinary alarm transmitting means is automatically operated prior to operation of the emergency alarm transmitting means.

15 9. In an alarm system as claimed in claim 7, in which the means operated responsive to the interrupting of the alternating current in said simplex circuit is a relay that connects an interrupter to said alarm signal.

20 10. In an alarm system, a station, a central office, a line extending from said station to said

office, a simplex circuit including said line, a source of alternating current normally connected to said circuit, an alarm signal at said office, a relay at said office included in said circuit normally maintained energized by the flow of alternating current therein, means at said station for interrupting the flow of alternating current in said circuit, said relay deenergizing responsive to said interruptions in current flow, means controlled by the deenergization of said relay for 10 operating said signal, said relay also deenergizing responsive to the accidental opening of one of the line conductors of said simplex circuit.

11. In an alarm system as claimed in claim 10, 15 in which the accidental opening of one of the line conductors in said simplex circuit unbalances the circuit and thereby increases the impedance thereof sufficiently to prevent sufficient flow of alternating current to maintain said relay energized.

CHARLES F. FFOLLIOTT.

20
